MEANS FOR TRANSFERRING OBJECTS TO HOOK TYPE CONVEYERS

Filed Sept. 12, 1928

UNITED STATES PATENT OFFICE

FREDERIC R. COLBY AND ARNOLD L. LARSEN, OF TOLEDO, OHIO, ASSIGNEES TO THE SURFACE COMBUSTION COMPANY, INC., OF TOLEDO, OHIO, A CORPORATION OF NEW YORK

MEANS FOR TRANSFERRING OBJECTS TO HOOK-TYPE CONVEYERS

Application filed September 12, 1928. Serial No. 305,458.

This invention relates to improvements in means for transferring objects from one support to another and more particularly for transferring coils of wire from a temporary carrier to a travelling conveyer as, for example, a furnace conveyer.

It is an object of the invention to provide means for transferring coils of wire to hooks forming part of a conveyer from a suspended position on a carrier which is movable toward and away from the conveyer.

In accordance with this invention, a coil of wire is first suitably hung on the end of a swingable carrier or beam and the beam manipulated in a manner to transfer the coil to a hook which forms part of a conveyer element. The invention has been particularly designed for loading coils of wire on an endless conveyer travelling along the roof of a heat-treating furnace but is not limited in its application to such use.

Referring to the drawing wherein the preferred embodiment of the invention is shown:

Fig. 1 is a vertical cross section of a tunnel like heat-treating furnace having a conveyer operating through the roof thereof and the wire coil transferring means constructed in accordance with the present invention in position for transferring a coil of wire to the conveyer hook;

Fig. 2 is an enlarged detail sectional view taken on line 2—2 of Fig. 1; and

Fig. 3 is an enlarged detail view of the hanger or saddle on which the wire coil will ordinarily be carried in order to permit the coil to be hung on the carrier and transferred therefrom to the conveyer hook.

In the drawings, 10 indicates generally a heat-treating furnace of any approved construction and fired in any suitable way. The roof 12 of the furnace is provided with a longitudinally extending slot 14 through which extends a series of hooks 16 which are secured at their upper ends to a conveyer element 18 which straddles the top of the slot 14 and which is provided with rollers 20 for travelling in a track 22 on each side of the slot. The conveyer element and its hooks 16 together form a travelling conveyer which is

caused to travel lengthwise of the slot 14 by any suitable driving means, not shown.

In one of the side walls of the furnace is a vertical slot 24 of a width suitable for its intended purpose, namely, to permit a temporary-coil supporting carrier or beam 26 to pass through the slot with a coil of wire W suitably supported at the end thereof. The beam 26 has projecting upwardly therefrom a post 28, the upper end of which is pivotally secured as at 30 to the upper end of a pedestal or link 32 which is pivoted at its lower end as at 34 to the metal framework or buckstays 36 of the furnace. The outer end of the beam 26 is slotted as at 38 and projecting through this slot is a pin or rod 40 which is carried by the upright support generally indicated at 42. It will now be seen that the beam 26 is capable of movement toward and from the conveyer hook 16, the outer end of the beam having a sliding motion with respect to its supporting pin 40 and the other end of the beam travelling in an arcuate path.

At the inner or coil supporting end of the beam 26 is a transversely extending shaft 44 (see Fig. 2) at the extremities of which are fixedly secured a pair of elbow levers generally indicated at 46. The upwardly projecting end of the elbow levers is provided with a depressed seat 48, the seat being adapted to receive the opposite end of a shaft 50 which projects through a jaw 52 of a wire supporting saddle generally indicated at 54. This saddle may, for convenience of description, also be termed an object supporting member. The laterally extending arms 56 of the elbow levers 46 are adapted to coact with a transversely extending latch bar 58, which is appropriately mounted in the beam 26 as in a slot 60. When the latch 58 is pushed forwardly the elbow levers are locked against rotation. Suitably secured to the latch bar 58 is an operating rod 62 which extends lengthwise of the beam 26 and which at its outer end is secured to a depending operating lever 64 suitably pivoted to the beam. It will now be seen that the elbow levers constitute tiltable means on which the saddle or object supporting member may be releasably supported.

The object supporting member or saddle 54 is provided with a plurality of laterally extending hook-like arms 66, these arms serving to support a bundle of coiled wire as will be readily understood. In the operation of placing a wire coil W on the saddle 54, the saddle supporting end of the beam 26 will, of course, be outside of the furnace. The shaft 50 of the saddle will be positioned on the upper ends of the elbow levers 46, the latch 58 holding the levers against rotation, and the coil of wire then hung on the hooks or arms 66 of the saddle. When the coil is supported on the beam as aforesaid, the beam is moved into the furnace through the slot 24 in the side thereof and when a conveyer hook 16 is in line with the space 51 between the jaws 52 of the saddle 54, the latch 58 is withdrawn from the elbow lever arms 56 whereupon the elbow levers will rotate by reason of the load thereon and transfer the saddle to the hook 16, the latter engaging under the shaft 50 between the saddle jaws 52, as will now be readily understood.

In order to prevent the hook 16 from swinging in a direction away from the adjacent end of the beam 26, during the coil transferring operation, there is provided in the roof of the furnace an abutment rail 68 which extends in parallelism with the slot 14 in the roof, the back of the hook being adapted to abut against the rail 68. That portion of the roof in front of the hook is preferably in upwardly step relation with respect to the abutment rail 68 in order to provide proper clearance for the free operation of the coil shifting mechanism.

Any suitable means may be provided for moving the beam 26 on its supports without departing from the spirit of the invention thus far described. However, the beam moving mechanism now to be described is preferred. Suitably supported above the top of the furnace as on an upright support 70 is an electric hoist 72 of any suitable or preferred type. Individually operable hoist controlling elements extend from the hoist to a convenient position near the beam 26, these elements terminating in operating handles 74 and 76. The hoist has a winding drum 78 from which extends a cable 80, this cable passing under a roller 82 mounted on the support 70, over and under a roller whose axis is concentric with the pivot 30 between the upstanding link 32 and the upstanding post 28 on the beam 26, the cable being finally anchored as at 84 to the upright support 70.

Assuming that the beam 26 is in the position shown in Fig. 1 and that it is desired to withdraw the beam from the furnace, the operator pulls down on the controlling handle 76 whereupon the electric hoist allows the cable 80 to unwind and consequently allows the beam 26 to pass out of the furnace. When

it is desired to insert the loaded beam into the furnace, the operator pulls on the controlling handle 74 whereupon the hoist is actuated to wind up on the cable 80 and consequently to move the beam into the furnace. Certain well known mechanism not necessary to be described determines the number of revolutions which the hoist drum 78 will make on any given actuation of the hoist.

In order to cushion the beam 26 as it moves into the furnace, there is mounted on a transversally extending support 86 above the furnace an elbow lever 88, the lower arm of which has a lateral extension 89 which projects into the path of the beam supporting link 32. Anchored to the support 86 and passing through the upper arm of the elbow lever 88 is a rod 90 and between the upper end of the rod 90 and the lever arm through which it passes is a coiled spring 92. This spring serves to cushion the final inward movement of the link 32 as will now be readily understood. This cushioning device also serves to initiate outward movement of the beam 26 when the electric hoist 72 is actuated to allow the beam to pass out of the furnace.

In order to provide proper light conditions so that the operator may clearly see when a conveyer hook 16 is in proper position to receive the saddle 54, there is provided in the remote wall of the furnace an electric light 94.

The present invention is particularly well adapted for use with wire annealing furnaces and offers a simple and practical means for loading wire coils on an overhead type of furnace conveyer. The invention is particularly well adapted with furnaces of the type shown in Patent 1,674,407.

What is claimed is:

1. The combination with a travelling conveyer and an object-supporting member adapted to be removably suspended thereon, of a carrier for said member movable toward and away from said conveyer, shiftable means carried by said carrier and adapted to releasably support said member, and means for releasing said means whereby said member may be shifted from the carrier to the conveyer.

2. The combination with a travelling conveyer and an object-supporting member adapted to be removably suspended thereon, of a carrier for said member movable toward and away from said conveyer, tiltable means supported by said carrier and adapted to releasably support said member, and means for releasing said means whereby said member may be shifted from the carrier to the conveyer.

3. The combination with a travelling conveyer and an object-supporting member adapted to be removably suspended thereon, of a carrier for said member movable toward and away from said conveyer, an up-

right arm pivoted at its lower end to said carrier and having its upper end in advance of its pivot, the upper end of said arm being adapted to support said member, and means for releasing said arm to permit it to swing toward the conveyer whereby said member may be shifted from the carrier to the conveyer.

4. In combination, a beam supported for movement in a vertical plane, an upright arm pivoted at one end of the beam, the upper free end of said arm being adapted to support an object when the arm is in upright position, a conveyer having hooks arranged for travelling past said arm, and means for releasing said arm whereby it may swing toward a conveyer hook as it passes the arm.

5. In combination, a beam supported for movement in a vertical plane, an upright arm pivoted on a transverse axis at its lower end to said beam, a conveyer having a series of hooks arranged for travelling in a path below the upper end of said arm, and means for releasing said arm whereby it may swing toward a conveyer hook, the top of the arm being adapted to support an object when in upright position.

6. In combination, a beam supported for movement in a vertical plane, an upright arm pivoted on the beam for movement in a vertical plane, the upper end of the arm being adapted to support an object, an object-supporting conveyer element movable past the arm below the top thereof, and means for releasing the arm for swinging movement toward the path of the conveyer element.

7. In combination, a beam supported for movement in a vertical plane, an arm pivoted on the beam for swinging movement in a vertical plane, means for releasably holding the arm in upright position, the upper end of said arm being adapted to support an object when the arm is in upright position, and a travelling object-receiving element movable in a path adjacent said arm and below the top thereof whereby when the arm is released the object carried thereby may be deposited on said element.

8. In combination, a beam supported for movement in a vertical plane, an object-supporting member supported by the beam and movable in an arcuate path in a vertical plane, a travelling object-supporting means movable in a path which will intersect the arcuate path of said means, and means for releasing said member for movement whereby an object carried by said member may be transferred to said object-supporting means.

9. In combination, a pedestal pivoted at its lower end, a beam pivotally supported by the upper end of the pedestal, movable means supported at one end of the beam for releasably supporting an object, a travelling object-supporting element movable in a path

below the object-supporting point of said means and in a plane close enough to said means to intersect its path of movement, means for releasing said means whereby the latter may transfer an object to said element, and power operated means operatively connected to said beam for moving it toward and from said object-supporting element.

10. In combination, means forming a chamber having an opening through a side wall thereof, a pivoted pedestal in front of said opening, a beam pivotally hung from said pedestal and projectable into the chamber through said opening, an object-conveying mechanism movable in a path below the roof of and in a plane extending lengthwise of the chamber, means supported by the beam for transferring an object carried thereby to said mechanism, power-operated means for moving said beam, and means disposed into relatively close proximity to the beam for operating said power-operated means.

11. In combination, an upright supporting element, a beam one end of which is slidably supported by said element, means between said element and the free end of the beam for supporting said free end of the beam for movement in an arcuate path in a vertical plane, said means including an upright link, means for positively moving the link in one direction, means for cushioning the final movement of the link in said one direction, means carried by the free end of the beam for releasably supporting an object, a travelling conveyer movable in a path in front of the free end of the beam and in relatively close proximity thereto, and means operable from a point remote from said free end of the beam for releasing said object-supporting means carried by said beam.

12. In combination, a furnace provided with an overhead conveyer adapted to convey annular objects in suspended position through the furnace, a member adapted to support the object and be coupled to the conveyer, a carrier on which said member may be hung prior to transfer to the conveyer, said carrier being movable into position adjacent the conveyer, and means on said carrier for extending its effective length into the path of the conveyer whereby said member may be transferred to the conveyer.

13. In combination, a furnace provided with an overhead conveyer, having hooks depending through a slot in the furnace roof, means for depositing objects on the hooks as they pass a given point comprising an elongated carrier on one end of which the object may be temporarily hung, means permitting forward and upward movement of said carrier into relatively close proximity to the conveyer, and means on the carrier for transferring said object onto a hook of the conveyer.

14. In combination, a furnace provided

with a slot in its roof, an overhead conveyer having hooks depending through said slot, means for depositing objects on said hooks as the latter pass a given point comprising an arm adapted when in upright position to support the object to be transferred, and means permitting said arm to tilt toward said conveyer to shift said object into the path of travel of said hooks.

10 15. In combination, a furnace provided
with a slot in its roof, an overhead conveyer
having hooks depending through said slot,
means for depositing objects on said hooks
as the latter pass a given point comprising an
15 arm adapted when in upright position to
support the object to be transferred, and
means permitting said arm to tilt toward
said conveyer, to shift said object into the
path of travel of said hooks, and means pre-
20 venting lateral displacement of the hooks
during the transfer of said object from said
arm to the conveyer.

In testimony whereof we affix our signatures.
